ATTACHMENT FOR BENDING MACHINES.

Application filed October 28, 1927. Serial No. 229,348.

This invention relates to bending machines of the type employed for the cold bending of structural steel or iron pieces such as angle, channel or I beams and has for its principal object to provide a new and improved construction of a device, which may either be in the nature of an attachment capable of being associated with existing machines or may be incorporated with the bending machine in the initial construction thereof, and by means of which channel iron or I beams may be bent in a manner not heretofore possible by such machine.

For the purpose of illustrating the nature of the present invention it has been shown as associated with a bending machine of the type in which three relatively large hardened steel rolls are mounted upon a suitable base in what may be termed a triangular arrangement with their axes extending vertically, two of said rolls being power driven and located at the ends of the base of the triangle while the third roll is an idler and has its axis located upon the line which bisects the base and therefore is equidistant from the two power driven rolls.

While bending machines of the above described type are capable of producing excellent results in the bending of many different types of structural steel or iron they are however limited in their application. For example, while the machines will bend channel or I beams to form rings or segments, they can bend such beams to form curves only wherein the axis of the radius of the curvature extends parallel to the web of the beam but can not successfully bend curves wherein the axis of the radius of curvature extends perpendicular to the web.

The object of the present invention is to provide a device which will enable curves of the latter type to be bent as readily in the machines as curves of the former type.

The above and other objects of the invention will appear more fully from the following more detailed description and by reference to the accompanying drawings forming a part hereof and wherein Fig. 1 is a plan view indicating diagrammatically the rollers of a bending machine of the type hereinbefore referred to and the application to such a machine of an attachment constructed in accordance with the principles of the invention; Fig. 2 is an enlarged side elevation of the attachment, part thereof being shown

in section and the cross section of a piece of channel iron being shown in dotted lines; Fig. 3 is a front elevation of the structure as seen from the left hand side of Fig. 2; Fig. 4 is a section on the line 4—4 of Fig. 2 and Fig. 5 is a view similar to Fig. 3 of a modification.

As shown in Fig. 1 of the drawing, the numerals 10, 11 and 12 indicate the rolls of a bending machine of the type hereinbefore referred to, the rolls 11 and 12 being rotated by any suitable means and being located in fixed spaced relationship. The roll 12 is an idler roll and in accordance with the usual constructions of such machines, said roll is adjustable to and from the rolls 10, 11 along a line which extends perpendicular to a line passing through the axes of the rolls 10, 11. The constructional details of the means for driving the rolls 10, 11 and the means for adjusting the roll 12 are not shown in the drawing as such means are old in the art and moreover form no part of the present invention.

In accordance with the present invention we provide any suitable block or bracket, such as indicated by the reference numeral 13, and which is adapted to be secured, as by the bolts 14, to the bed plate of the bending machine. The bracket 13 is preferably located midway between the rolls 10 and 11 and is provided with a dovetailed guideway 15 in which is slidably received a carriage 16. The carriage 16 has an upwardly extending flange 16^a to which is secured, as by the bolt 17, a knee bracket 18, the knee bracket being made vertically adjustable by the provision of an elongated slot in its vertically extending portion. The horizontally extending portion of the bracket 18 is also provided with an elongated slot 19 in which is received a flanged bearing 20 having a non-circular periphery which engages slidably but non-rotatably within the slot 19. Suitably secured to the bearing 20, for example by a pin 21, is a stud 22 preferably made integral with a carrier 23 the carrier thus being held, by the pin 21 and non-circular bearing 19, against rotation. Rotatably mounted in suitable recesses 24 formed at diametrically opposite points of the carrier are a pair of hardened steel rollers 25 which preferably rest upon balls 26. The rollers 25 are held within their respective recesses by a washer 27 confined between the top of the carrier 23 and the bottom of the bearing 20.

Instead of employing rollers, any suitable anti-friction devices such as the balls 28 shown in Fig. 5 may be used.

The manner in which the device is used is as follows:

If it is desired to bend a length of channel iron 30 in a curve the axis of whose radius of curvature extends at right angles to the web of the iron, the block 13 is bolted to the base 10 of the machine in the position shown in Fig.

1. The carriage 16 and knee bracket 18 are then adjusted according to the dimensions of the channel iron to be bent and a carrier 23 and rollers 25 are selected which will fit neatly 15 between the flanges of the channel iron as indicated in Fig. 2. The iron 30 is then placed between the rolls 10, 11, 12 with its flanges extending upwardly and spanning the carrier and rollers 25. The bending machine is then 20 started to cause the power driven rolls to draw the iron through the machine and as the bending operation proceeds the roller 12 is moved inwardly to produce the required pressure for forming a bend of the desired curvature. It 25 will be understood that the direction of rotation of the rolls 10, 11 is periodically reversed to draw the iron back and forth between them and the roll 12.

It will be noted that the axes of rotation of 30 rollers 25, and also the balls 28, are located in the same plane as the axis of the roll 12 and that the periphery of each of said rollers, or each set of balls 12, contacts along vertical lines with the inner wall of the flange of the 35 channel iron with which they are in engagement to form a pair of rotary reaction supports, the lines of contact of which with the flanges of the iron are located in substantial alignment with the contacting surface area 40 between the periphery of the roll 12 and the outer walls of said iron. The pressure exerted by the roll 12 upon the flange with which it contacts is therefore transmitted through the said flange to the rollers 25 (or 45 balls 28), and carrier 23 and to the opposite flange. During the bending operation the roller 25 nearest to the roll 12 will always rotate oppositely to the latter, thus producing a rolling action on opposite sides of the flange 50 at the inner side of the curve in the direction in which the iron is at any time in movement and consequently there is no scoring or gouging of the surface skin of the iron. The same is also true of the rotation of the other roller 55 25 relatively to the rolls 10 and 11. As the rotation of the rollers 25 are opposite in direction no torque is exerted on the carrier 23 and consequently the small pin 21 is sufficient to hold the carrier in a position in which the axes 60 of the rollers are maintained in the same plane as the axes of the roll 12. We have found in practice that it is not necessary to extend the rollers 25 to the bases of the flanges, as apparently the presence of the mass of material in the web of the iron serves to prevent 65

distortion of the flanges adjacent to said web.

The construction of the bending machines of the prior art such as have been hereinbefore described, and particularly of the roll type, can not be employed for bending channel or I beams wherein the axis of the radius of curvature of the bend extends perpendicular to the web of the beam because of the fact that when it is desired to make such a bend the side flanges of a channel iron, for example, are subjected to pressure upon their outer sides only, and as there is nothing to support these flanges on their inner sides the result is, when it is attempted to produce a bend of the type described, that the side walls are crushed or bent inwardly thereof in effect collapsing the beam and distorting it to such an extent that it is entirely useless.

With the present invention a very substantial bracing structure is provided between the inner walls of the flanges so that the pressure exerted by the middle one of the three rolls of the bending machine is in effect distributed through our device to both flanges and distortion is absolutely prevented.

While we have shown the invention in its preferred form as embodying rolling members which contact with the inner walls of the flanges of the structural beam, it will be understood that the use of such rolling members is not absolutely essential but that a rigid member could be employed as long as the principle of maintaining substantially a line contact between the reaction support and inner walls of the flanges is adhered to.

It will be understood that the principles of the invention are not limited to the specific details of the constructional example selected for the purpose of illustration but that many changes, variations and modifications of such details may be resorted to without departing from the spirit of the invention.

We claim:

1. The combination with a bending machine having a plurality of bending rolls, of a reaction support including a plurality of rolling members adapted to fit neatly between and to contact with the inner walls of a pair of spaced flanges of a piece of structural iron as the latter is subjected to a bending operation in said machine, said rolling members contacting with said flanges along lines opposite to the contacting area of the periphery of one of said rolls with said piece and the axes of said one roll and rolling members being located in the same plane.

2. A device adapted to be used in combination with a bending machine of the roll type, said device including a carrier having a pair of spaced recesses, rolling members rotatably supported in said recesses and means to secure said carrier to said machine with the axes of said rolling members located in the same plane as the axis of one of the rolls of said bending machine.

3. The combination with a bending machine having a plurality of bending rolls, of a reaction support including a plurality of rolling members adapted to fit neatly between and to contact with the inner walls of a pair of spaced flanges of a piece of structural iron as the latter is subjected to a bending operation in said machines, said rolling members contacting with said flanges along lines 5 opposite to the contacting area of the periphery of one of said rolls with said piece and the axes of said one roll and rolling members being located in the same plane and means to secure said reaction support to said machine and to maintain said rolling members in said plane during a bending operation.
- 10 4. The combination with a bending ma-

chine having a plurality of bending rolls, of a reaction support adapted to fit neatly between, and to contact with, the inner walls 20 of the spaced flanges of a piece of structural iron as the latter is subjected to a bending operation in said machine, said reaction support being constructed and arranged to contact with each flange with substantially a line 25 contact, and said contact lines being located opposite to the contacting area of the periphery of one of said bending rolls with said piece, and the axis of said one roll and said contact lines being located in the same plane. 30

In testimony whereof we have hereunto set our hands.

RAYMOND L. HERMAN.
